(57) **CLAIM**

The ornamental design for a disc brake caliper as shown and described.

DESCRIPTION

1. Disc brake caliper

1.1 : Perspective

1.2 : Left

1.3 : Right

1.4 : Front

1.5 : Back

1.6 : Top

1.7 : Bottom

1.8 : Bottom perspective view

The design relates to a caliper for disc brake, as illustrated in the representations; The broken lines depict portions of the model that form no part of the claimed design. The other lines represented, in some parts of the product, are the shading, in order to be in compliance with U.S. regulation.
